UNITED STATES PATENT OFFICE.

JOHN L. DIBBLE, OF BROOKLYN, NEW YORK.

GAME BOARD OR TABLE AND APPURTENANCES THERETO.

SPECIFICATION forming part of Letters Patent No. 283,869, dated August 28, 1883.

Application filed March 7, 1883. (No model.)

To all whom it may concern:

Be it known that I, JOHN L. DIBBLE, a citizen of the United States, residing at Brooklyn, in the county of Kings, in the State of New York, have invented a new and useful Improvement in Game Boards or Tables and Appurtenances Thereto; that the same has not been patented by me, nor to my knowledge by any other person in any foreign country, and that the same has not to my knowledge been in public use at any time or in any place, of which the following is a specification, reference being had to the accompanying drawings, which form a part of this specification.

Figure 1 represents a plan of the improved board or table, with the two sets of checkers or playing-pieces placed in position for beginning the game. Fig. 2 is an outline plan of a similar board or table, the playing-spaces being numbered to facilitate the explanation of the methods of arranging the contrasting colors of the playing-spaces and of using the device.

My invention comprises an improved form of checker and chess board or table, and of the checkers to be used with it. It may be made of any suitable material, and may be mounted in any desirable or convenient form, from a simple card or board to an ornamental table that may also serve as an article of household use or ornament. In this specification I shall speak of it as the "board," without regard to the form or manner in which it may be mounted.

The well-known games of checkers or draughts and of chess are usually played upon a board which is divided into sixty-four square spaces, generally of two contrasting colors. My improvement consists in substituting for these square spaces spaces of hexagonal form. This arrangement permits the convenient use of a greater number of checkers on a board of given dimensions in the game of checkers, and in both the game of checkers and the game of chess it affords a greater variety of moves to the playing-pieces, and renders many new and pleasing variations of the games practicable.

The games of checkers and of chess are played subject to rules which are well known to those skilled, and which are also published in treatises and text-books on the subjects. It is therefore unnecessary to introduce them

in this specification, and I shall refer to them as the regular rules of the game.

In Fig. 1 the spaces that are shaded with 55 lines in the direction from *a* to *d* represent spaces of one color, those shaded with lines in the direction from *b* to *c* represent spaces of another color, and those spaces which are left unshaded represent spaces of a third color. 60 The choice of colors may be according to taste, or other distinguishing-marks than colors may be employed; but I deem contrasting colors the simplest and most effectual. In arranging the order of these colors it is important that 65 no two immediately-adjoining spaces be made the same color. To insure a correct arrangement I proceed as follows, (see Fig. 2:) First, I make the row of spaces numbered 1 to 4, say, white; next I make the row of spaces numbered 5 to 8, say, blue; next I make the row of spaces numbered 9 to 12, say, red. Repeating, I make the row of spaces numbered 13 to 16 white, and continue the alternation of colors in same order until the colors of all 75 the spaces are determined. Any other colors than white, blue, and red may be employed.

I provide for use with the board a set of checkers of the usual form—that is, suitably formed and colored disks of wood or other 80 suitable material—consisting of forty-eight pieces, twenty-four checkers or pieces being assigned to each of the opposing sides or players, the twenty-four checkers assigned to one side being of one color, and the twenty-four 85 checkers assigned to the other side being of another and contrasting color—as, for instance, black and white. One-half (or twelve) of the checkers assigned to one side are to bear a distinguishing-mark—as a depression or a raised 90 spot in the center—and one-half of the checkers assigned to the other side are to bear a similar distinguishing-mark; or of the twenty-four checkers of one side one-half may be of a light color and one-half of an approximate 95 color, and of the twenty-four checkers of the opposing side one-half may be of a dark color and one-half of an approximate color—for example, white and yellow on the one hand and black and brown on the other. The object of 100 thus distinguishing the checkers will be hereinafter explained.

With the board and checkers as described the game of checkers may be played in a va-

riety of different ways, each affording the players opportunity to use their skill in a different manner—as, for examples:

First. What I call the “full game,” played between two players: The checkers being placed on the board, as shown in Fig. 1, the circles described with light lines representing the light-colored checkers and the circles described with heavy double lines representing the dark-colored checkers, and small central circles in either case representing the distinguishing-marks, (depressions or raised spots,) as before described, one player using the entire group of checkers on the side of the board $a\ b$, and the other player using the entire group on the side of the board $c\ d$, the players playing alternately. The player may move a single checker of his own group to an unoccupied space immediately adjoining, either directly or obliquely forward toward the side occupied by the other player, or he may capture one of his opponent’s checkers adjoining one of his own by “jumping” it—that is, by passing his checker over it to the space on the opposite side of the checker to be captured, provided that this space on the opposite side of the checker to be captured is unoccupied, and that the movement of the jumping checker be obliquely forward toward the side occupied by the opposing player. The game is continued, the movement of the checkers being governed by the regular rules of the game of checkers, except that the players have the option of moving either directly or obliquely forward, it being understood that the spaces corresponding with the spaces numbered consecutively from 1 to 8 in Fig. 2 will serve for the “king-row” on the one side, and the spaces corresponding with those numbered consecutively from 57 to 64 in Fig. 2 will serve in like manner for the other side. It will be found that the option of moving the checkers either directly or obliquely forward permits many new combinations for attack or defense.

Second. A game between four players, two playing as partners against the other two as partners. The checkers being arranged as in Fig. 1, one player using the twelve checkers grouped nearest the corner of the board a , and his partner using the twelve checkers grouped nearest the corner of the board b , these twelve checkers being of the same color as those of his partner, but bearing the distinguishing-marks hereinbefore described, or being of an approximate color to those of his partner, the other two players playing as partners using the similar groups of checkers nearest the corners c and d , the players will play alternately. Thus, if player at a play first, the player at d will follow next, player at b will play; and player at c will follow; player at a now plays again, and in this order the game is continued in the manner described in the first example.

Third. Again between four players each playing independently. The checkers being placed, one group of twelve being apportioned

to each player, as in the second example, the players play alternately in the following order: first the player at a ; second the player at c ; third the player at b ; fourth the player at d , the players a and b having the privilege of capturing the checkers of the players c and d , and the players c and d having the privilege of capturing the checkers of the players a and b ; and should either player get a king he will then have the privilege of capturing (with his king) the checkers of either of the other players, the game being continued until all the checkers of three of the players are captured, the fourth player being the winner.

Fourth. The board may be used to play a game of checkers between two players in accordance with the regular rules of the game without variation, except as to the number of 85 checkers employed, one player playing from the side of the board $a\ c$, arranging his checkers on the three rows of spaces nearest that side, the other player playing from the side $b\ d$ and arranging his checkers on the three 90 rows of spaces nearest that side, the play being conducted in accordance with the regular rules.

Fifth. The board may be used in a manner similar to that described in the fourth example 95 by four players, either each playing independently, or two playing as partners against the other two as partners, by playing from the sides, as described, and placing the checkers on the rows of spaces mentioned in the fourth 100 example, the checkers apportioned to either player being grouped in the corner nearest that player, it being observed that when two are playing as partners against the other two as partners they play in a similar order to 105 that described in the second example, and that when the players are playing independently they play in similar order and capture checkers on the conditions described in the third 110 example.

Many other modifications may be made in the methods of playing the game of checkers on this board—as, for instance, a less number of checkers may be employed, or they may be arranged differently at the opening of the 115 game, or the regular rules of the game may be modified in other manner than that I have described; but I deem the foregoing examples sufficient to explain to those skilled in the game the use of the invention.

In using the board to play the game of chess, the regular and well-known set of chessmen are to be employed. The following is what I deem to be the best arrangement of the chessmen at the opening of the game, referring to 125 Fig. 2, one player occupying the side of the board, $a\ b$, and the other the opposite side, $c\ d$, the pieces of the player $a\ b$ being placed in the following order: On space numbered 1 a rook or castle; on space numbered 5 a knight; 130 on space numbered 2 a bishop; on space numbered 6 the queen; on space numbered 3 the king; on space numbered 7 a bishop; on space numbered 4 a knight; on space numbered 8 a

rook or castle; on the spaces numbered consecutively from 9 to 16 the eight pawns, the chessmen of the other player being arranged similarly on the opposite side of the board. It will be observed (see Fig. 1) that there are eight rows of alternately-colored spaces running in the direction from *a b* to *c d*. These I call "parallels of alternate color." That there are sixteen rows of four similarly-colored spaces running in the direction from *a c* to *b d*. These I call "parallels of single color." It will further be observed that there is a double series of diagonal or oblique rows of spaces, the number of spaces in each varying according to its position in the group—first, rows of alternately-colored spaces crossing the board diagonally from the sides *c a b* to the sides *c d b*, and from the sides *a c d* to the sides *a b d* at an angle of sixty degrees from the sides *a c* and *b d*, and at an angle of thirty degrees from the sides *a b* and *c d*. These I call "diagonals of alternate color;" second, rows of similarly-colored spaces crossing the board diagonally from the sides *c a b* to the sides *c d b*, and from the sides *a b d* to the sides *a c d* at an angle of sixty degrees from the sides *a b* and *c d*, and at an angle of thirty degrees from the sides *a c* and *b d*. These I call "diagonals of single color." In order to make this combination of parallel and diagonal rows of spaces available in playing the game of chess with the usual set of chessmen, modifications of the moving-powers of the various pieces are necessary, and the following moves are what I deem the best for the various pieces—viz., that the king may be moved to any space immediately adjoining the one on which it stands, or to the next adjoining space on the parallel of single color on which it stands. Thus, if standing on space numbered 30, Fig. 2, it will command the spaces numbered 22, 26, 27, 29, 31, 33, 34, and 38. That the queen may be moved along either series of parallels or either series of diagonals over any number of unoccupied spaces. Thus, if standing on space numbered 30 in Fig. 2, it will command the diagonals of alternate color beginning with the spaces numbered 16 and 17, and ending with the spaces numbered 41 and 48, the diagonals of single color beginning with the spaces numbered 5 and 7 and ending with the spaces numbered 55 and 53, the parallel of alternate color beginning with the space numbered 6 and ending with the space numbered 62, and the parallel of single color beginning with the space numbered 29 and ending with the space numbered 32. That the bishops may be moved along either series of diagonals any distance, provided the intervening spaces are unoccupied. Thus, if standing on space numbered 30, Fig. 2, it will command the diagonals of alternate color beginning with the spaces numbered 16 and 17 and ending with the spaces numbered 41 and 48, and the diagonals of single color beginning with the spaces numbered 5 and 7 and ending with the spaces numbered 55 and 53. That the knights may be moved one

space on the diagonals of single color or two spaces on the diagonals of alternate color, (whether the intermediate space on the diagonal of alternate color thus passed over be occupied or not.) Thus a knight standing on the space numbered 30, Fig. 2, will command the spaces numbered 18, 19, 21, 23, 37, 39, 42, and 43. That the rooks or castles may be moved along either series of parallels any distance over unoccupied spaces, or they may be moved one space along either series of diagonals. Thus a rook standing on space numbered 30, Fig. 2, will command the parallel of alternate color beginning with the space numbered 6 and ending with the space numbered 62, the parallel of single color beginning with the space numbered 29 and ending with the space numbered 32, and the spaces numbered 18, 19, 26, 27, 33, 34, 42, and 43. With these modifications the game may be played substantially in accordance with the regular rules of the game of chess. In stating these modified moves as being in my judgment the most suitable to adapt the game of chess to be played upon this board I do not fix them arbitrarily. Those skilled in the game may modify them as they deem expedient.

Modifications may be made in the plan of the board without departing from the principle of the invention, as the group may contain more than sixty-four spaces; but as this number is ample for either two or four players in the game of checkers, and is adapted for the game of chess with the usual set of chessmen, I consider this number generally sufficient. The number of spaces may be reduced. This will permit the game of checkers being played in several forms with a less number of men or checkers.

I claim as my invention—

1. A checker and chess board having a rectangular group of adjoining hexagonal playing-spaces arranged substantially as and adapted to be used as herein described.

2. As an accompaniment to a game-board, a set of checkers consisting of forty-eight pieces, of which twelve are of one color, twelve are of the same color and bear a distinguishing mark, twelve are of a contrasting color, and twelve are of the same contrasting color and bear a distinguishing mark, substantially as described.

3. As an accompaniment to a game-board, a set of checkers consisting of forty-eight pieces, of which twelve are of one color, twelve are of a contrasting color, twelve are of an approximate color to the first color, and twelve are of an approximate color to the second color, substantially as described.

In testimony whereof I have hereunto set my hand at Brooklyn, New York, in the presence of two subscribing witnesses.

JOHN L. DIBBLE.
